UNITED STATES PATENT OFFICE.

WILLIAM C. CROSS, OF BOSTON, MASSACHUSETTS.

MACHINERY FOR THE MANUFACTURE OF PAPER BAGS.

SPECIFICATION forming part of Letters Patent No. 363,729, dated May 24, 1887.

Application filed November 16, 1886. Serial No. 219,039. (No model.)

To all whom it may concern:

Be it known that I, WILLIAM C. CROSS, of Boston, in the county of Suffolk and State of Massachusetts, have invented certain new and 5 useful Improvements in Machinery for the Manufacture of Paper Bags, of which the following is a specification.

My invention has relation to that kind of paper-bag machines of which the machine described and shown in Letters Patent No. 116,842, of July 11, 1871, may be taken as the type—that is to say, machines in which a "plate-knife folder" (whether reciprocatory or moving continuously in one direction) is combined 10 and adapted to operate in connection with a "guide-finger," for the purpose of forming the first or "diamond" fold; and my invention may be stated in general terms to consist in combining with the plate-knife folder a "creaser-roll," beneath which the plate-knife folder passes, said roll acting to crease and break down the edges of the diamond fold before the bag reaches the feed-rolls beyond.

While my invention is adapted to be used 25 in any machine employing a plate-knife folder, it has, however, been devised with more particular reference to the requirements of paper-bag machines such as are illustrated and described in a number of patents heretofore 30 granted to me—as, for instance, in my Letters Patent No. 325,059, of August 25, 1885, and No. 336,474, of February 16, 1886.

In the accompanying drawings, which will be hereinafter more particularly referred to, I 35 have represented my invention as applied to and embodied in the machine which is the subject of my last-named Letters Patent No. 336,474. In the practical operation of such machinery, the plate-knife folder, (which rotates or moves 40 continuously in one direction,) when it rises after the first fold is laid, lifts with it the rear or overlying portion of said fold. This action, particularly in operating with heavy paper, is apt to disarrange the parts of the fold, particularly along the opposed V-shaped side 45 edges of the fold, (which are practically uncreased,) the consequence of which is that when the bag-blank passes between the presser-rolls, the fold is apt to be pressed awry, or its V side 50 edges are apt to be crumpled and creased unevenly. The creaser-roll above referred to

remedies this difficulty. I arrange said roll in advance (relatively to the direction of feed) of the point where the plate-knife folder quits the blank, so that the side edges of the fold will be flattened and definitely creased before the plate-knife folder rises. By this operation the fold is put in such condition that after it is lifted by the plate-knife folder it will fall back into its original position, the creases determining and assuring the proper outlining of the fold during its subsequent passage between the other rolls of the machine.

In the accompanying drawings, Figure 1 is a plan of so much of the machine as needed to illustrate my invention. Fig. 2 is a section of the same on line 2 2, Fig. 1, the near sprocket-chain being removed in order to permit a full view of the bag-blank. Fig. 3 is a plan of a blank with the first fold laid similar to Fig. 7 of the drawings accompanying my Patent No. 336,474.

The machine in its general organization resembles that shown and described in my said Letters Patent No. 336,474.

D D are the rolls carrying sprocket-wheels E E. F F are sprocket-wheels, which, in conjunction with wheels E E, carry sprocket-chains G, on which are mounted the plate-knife folders H.

K K' are the presser and cutting rolls, by which the uncut central portion that connects successive bag-blanks is severed.

I is the guide-finger attached to a cross-bar, m, and having connected with it the "former-plate" b and the "lap-guide" d.

The general construction, combination, and mode of operation of these parts are the same as described in my aforesaid Letters Patent with reference to the correspondingly-lettered parts therein shown, and require therefore no explanation here. I have omitted from the drawings the "former," the mechanism or devices for preliminarily cutting and slitting the blank, and the "spring-opener strip," inasmuch as these instrumentalities involve merely preliminary operations and are not essential to an understanding of my improvement. I therefore proceed to a description of the features in which my present invention is comprised.

At a point between the front sprocket-wheels, F, and the heel of the former-plate b is the roll

V, which I term the "creaser-roll." This roll is supported in suitable bearings in the frame of the machine above the table J, over which the blanks travel, and in position to bear down 5 upon the blanks. The plate-knife folders H pass between this roll and the table, and to permit the roll to accommodate itself to this it is supported preferably in yielding bearings, as seen at s, Fig. 2. The roll is driven at suitable 10 speed so as to travel at about the same rate with the blank, and for this purpose may take its motion from any convenient driven part of the machine. In this instance it gets its motion through pulleys and a belt, t, from the upper 15 one of a pair of rolls, X, (which in the working-machine are the "paste-rolls.")

The operation is as follows: The front end of the blank as it travels beyond the former-plate, with the first fold in condition to be laid, 20 passes beneath the creaser-roll, which bears upon it and breaks down and definitely creases its V side edges v, (which edges are shown clearly in Fig. 3.) This takes place before the plate-knife folder H reaches the front sprocket 25 wheels, F. Consequently the fold is definitely broken down, laid and creased at its side edges before the plate-knife folder begins to rise and quit the blank. The effect of this operation and the advantages flowing therefrom have 30 been above set forth.

In the particular machine shown in the drawings the side flaps, y, of the first fold are, by the lap-guide d, held up until after the first fold travels beyond that guide, which latter, as 35 seen, extends nearly to the heel of the former-plate. It becomes necessary, therefore, under these conditions, to press with the creaser-roll upon only so much of the first fold as is included in the two triangular side spaces bounded

by the lines v and the dotted lines v' in Fig. 3. 40 To this end the creaser-roller is made, as shown in Fig. 1, with two cylindrical side pressing-surfaces, n n, and an intermediate recess, m', at the point where no pressure is to be exerted on the fold. 45

Having described my improvement and the best way now known to me of carrying the same into effect, what I claim herein as new and of my own invention is—

1. The combination, with the guide-finger 50 and the plate-knife folder, of the creaser-roll beneath which the plate-knife folder passes during the operation of forming the first fold, substantially as and for the purposes herein-before set forth. 55

2. The combination of the guide-finger, the plate-knife folder rotating or continuously moving in one direction, and the creaser-roll arranged to bear upon the blank between the guide-finger and the point where the plate- 60 knife folder rises to quit the blank, substantially as and for the purposes hereinbefore set forth.

3. The combination of the plate-knife folder rotating or moving continuously in one direction, the guide-finger, the former-plate, the 65 lap-guide, and the creaser-roll arranged to bear upon the blank between the heel of the former-plate and the point where the plate-knife folder rises to quit the blank, and formed with side bearing or pressing surfaces and an intermediate recess, substantially as and for the purposes hereinbefore set forth. 7c

In testimony whereof I have hereunto set my hand this 6th day of November, 1886.

WM. C. CROSS.
